United States Patent Office

Des. 227,116

Patented June 5, 1973

227,116

SPEAKER BOX

Kazuhisa Sato, Sagamihara, Japan, assignor to Sony
Corporation, Tokyo, Japan

Continuation of design applications Ser. No. 25,416, 25-
417, and Ser. No. 25,418, all Oct. 9, 1970, all now aban-
doned. This application Nov. 4, 1971, Ser. No. 195,901

Claims priority, application Japan Apr. 11, 1970;
Apr. 15, 1970; Apr. 21, 1970

Term of patent 14 years

U.S. Cl. D26—14   Int. Cl. D14—01

FIG. 2

FIG. 1

FIG. 3

FIG. 5

FIG. 4

FIG. 6

FIG. 7

FIG. 8

FIG. 9

FIG. 1 is a perspective view of a speaker box, showing my new design:

FIG. 2 is a top plan view thereof:

FIG. 3 is a side elevation thereof:

FIG. 4 is a perspective view of a second modified embodiment of the speaker box illustrated in FIG. 1:

FIG. 5 is a top plan view thereof:

FIG. 6 is a side elevation thereof:

FIG. 7 is a perspective view of a third modified embodiment of the speaker box illustrated in FIG. 1:

FIG. 8 is a top plan view thereof; and

FIG. 9 is a side elevation thereof.

This is a continuation of design applications Ser. No. D. 24,416, D. 24,517 and Ser. No. D. 25,418, each filed Oct. 9, 1970, and now abandoned.

I claim:

The ornamental design for a speaker box, substantially as shown and described.
